BUILDING BLOCK

John Joseph Olsen, San Francisco, Calif.

Application September 22, 1933, Serial No. 690,548

3 Claims. (Cl. 72—30)

The present invention relates to building blocks and wall construction and more particularly to improved blocks of light weight which can be laid up in opposed relation to form the inside and outside of a wall in a new and novel manner.

An object of the present invention is to provide building blocks of new and novel design which can be laid up in oppositely disposed staggered relation to form the inside and outside surfaces of a wall and layer upon layer in staggered relation to any desired height.

Another object of the invention is to provide a building block of comparatively light construction having projections upon one side which will interlock with corresponding projections upon a similar block when laid in opposed staggered relation and form a vertical cavity between the blocks into which an aggregate may be poured for the purpose of securing the blocks together.

Other objects and advantages of the invention will be in part evident and in part pointed out in the following description and the accompanying drawing wherein there is shown, by way of illustration and not of limitation, preferred embodiments thereof.

In the drawing:

Figure 1 is a fragmentary perspective view showing a portion of a wall built up with one form of block,

Figure 2 is a perspective view of a side wall block of the type illustrated in Figure 1,

Figures 3 and 4 are perspective views of specially formed outside and inside corner blocks for a wall of the type illustrated in Figure 1,

Figure 5 is a plan view of the section of wall illustrated in Figure 1 with the binding aggregate omitted,

Figures 6, 7 and 8 are modified forms of side wall forming blocks embodying the present invention, and

Figure 9 is a plan view of a section of side wall constructed with a block or slab such as is illustrated in Figure 8 of the drawing.

Referring to Figure 1 of the drawing, it will be seen that the two walls and the corner of a building made in accordance with this invention can be built up to form a rigid construction with only three distinctly different forms of blocks. These blocks are individually illustrated in Figures 2, 3 and 4 of the drawing and are designated by the numerals 10, 11 and 12. Each of the blocks 10 comprises a slab forming portion 13 having pro-

jections 14 formed upon one side thereof so that when the slab portions 13 are arranged in opposed and staggered relation the projections 14 upon the opposed slabs will interlock with each other and provide vertical cavities between the slabs into

60 which an aggregate 15, such as concrete or the

like, may be poured, as illustrated in Figure 1. Blocks constructed in accordance with this invention may be made of concrete, using stone or cinders, or any other suitable air or kiln drying plastic material. It is contemplated that the outer surfaces of the slab portions of the blocks 10, 11 and 12 will be smoothed or provided with a desired form of finish.

In order that the corner of the building may conform with the side walls the outside corner block 11 is provided with long and short finished sides 16 and 17 which extend at right angles to each other. This corner block 11 has a projection 18 which is adapted to cooperate with a similar projection 19 upon the inside corner block 12 and a second projection 20 which is adapted to cooperate with an oppositely projecting boss or member 21 upon the block 12. When the inside and outside corner blocks are arranged in reversed and overlapping relation, as illustrated in Figure 1 of the drawing, they will form a vertical cavity at the corner of the wall into which an aggregate can be poured, as is the case with the side wall forming blocks.

The block 12 has a slab portion 22 that extends outwardly from the inside corner of the building and carries a second projection 23 which will cooperate with a projection 14 upon one of the side slabs or blocks 10 and thus form a firm tie between the corner blocks and the side blocks in each alternate layer.

An inspection of Figure 1 of the drawing will show that the projection 20 upon the outside corner block will align vertically with the projecting bosses 21 on the inside corner blocks disposed at a right angle immediately below and there above to thus form the irregular cavity at the corner of the wall into which a binding aggregate may be poured, as previously described.

An additional feature of the blocks illustrated in Figure 1 of the drawing is in the provision of an enlarged end or foot portion 24 upon the projections 14, 18, 19 and 23. This enlarged end or foot portion 24, in addition to providing for an interlock between the inside and outside slabs at the corner and sides of the wall which will prevent a separation thereof, also provides steps within the vertical cavity formed whereby that will hold any aggregate poured therein in fixed vertical relation with the wall. For an illustration of this feature reference should be had to Figure 5 of the drawing, wherein the staggered relation of the foot portions 24, one above the other, is clearly shown.

It will be understood that the shape and disposition of the projections 18 and 20 and the projections 19, 21 and 23, upon the blocks 11 and 12 respectively, may be changed and that changes may also be made in the number and shape of

projections upon the side wall forming blocks without departing from the spirit of the invention. A modification in this respect is shown in Figure 6 of the drawing, wherein a block 25 is illustrated as having a slab forming portion 26 with a single projection 14.

In Figure 7 there is illustrated a block 27 having a slab forming portion 28 with two projections 29 of rectangular cross section. A modification of this latter form of block may also be obtained by forming the projections 19 with a dove-tail cross section.

In Figures 8 and 9 of the drawing there is illustrated a further modification of an improved side wall forming block having projections which interlock in the lateral and transverse directions so as to prevent both a separation of and a lateral movement between the opposed blocks. In this embodiment the block designated by the numeral 30 comprises a slab forming portion 31 having an outwardly extending hook like projection 32 with an upset base portion 33 that will engage the outside of an interlocking hook like portion 32 and prevent lateral displacement thereof. When the hook like projections 32 of opposed slabs 31 are assembled in opposed relation, as shown in Figure 9 of the drawing, they will form a vertical cavity into which cement or other aggregate 15 may be poured to hold the blocks securely together, as is the case with the construction illustrated in Figure 1.

In constructing a building with blocks of the type contemplated by the invention the corner and side blocks will be laid up with mortar, as is the standard practice. To secure a firm tie between the mortar and the edges of the slab portions, the blocks may be provided with complementary tongue and groove edges which will interlock with tongues and grooves formed upon adjacent slab portions. In connection with this aspect of the invention it should be stated that, since the corner blocks 10 and 11 must be reversed top for bottom, only grooves can be provided upon these blocks, unless right and left hand molds are used in forming the blocks. However, in the case of the side blocks a single mold can be used in forming all of these blocks.

When building a wall with these blocks the binding aggregate 15 can be poured into the vertical cavities as the wall is built up or it can be poured as a final operation after the wall has been completed to the desired height. If additional strength should be required, reinforcing irons 35 may be located in these cavities before the aggregate is poured therein. The provision of such reinforcing irons will not interfere with a pouring of the aggregate after the wall has been constructed. The particular shape of these improved blocks will also permit a pouring of the aggregate during the construction of the wall as the blocks can be laid around the upwardly projecting irons without being threaded therewith as would be the case were the cavities formed through a single block.

A further feature of advantage in a wall constructed in accordance with the present invention is that there will be provided vertical passageways between the opposed slab portions 13 and adjacent projections 14 through which the plumbing and electric wiring conduits may pass. These passageways will also permit the disposition of a flue therein if desired. In this latter event it is contemplated that the flue will be

formed with a standard fired-clay lining 35, as illustrated in Figures 1 and 5 of the drawing.

While I have, for the sake of clearness and in order to disclose my invention so that the same can be readily understood, described and illustrated specific devices and arrangements, I desire to have it understood that this invention is not limited to the specific means disclosed, but may be embodied in other ways that will suggest themselves, in view of this broad disclosure, to persons skilled in the art. It is believed that this invention is broadly new and it is desired to claim it so that all such changes as come within the scope of the appended claims are to be considered as part of this invention.

Having thus described my invention, what I claim and desire to secure by Letters Patent is—

1. A building block comprising a surface forming slab having two spacing projections formed upon the back surface thereof, said spacing projections being adapted to cooperate with like projections upon similar slabs and form a vertical cavity between the slabs into which an aggregate may be poured when a number of said slabs are laid up in two parallel courses, and an oppositely extending foot portion upon each of said projections adapted to extend into said cavity and interlock horizontally and vertically with said aggregate to secure the slabs together in opposed staggered and superimposed staggered relation to form the inside and outside surfaces of a wall.

2. A wall construction comprising a plurality of surface forming slabs laid layer upon layer in staggered relation to form one surface of a wall, other surface forming slabs laid layer upon layer in staggered relation with each other and in spaced and staggered relation with said first surface, forming slabs to form another surface of the wall, each of said slabs being similar in construction and having spacing projections which form a continuous vertical cavity into which a binding aggregate may be poured, and a laterally extending foot upon the end of each of said spacing projections adapted to project alternately in opposite directions and interlock with said aggregate to secure the slabs together against displacement in both a horizontal and a vertical direction.

3. In a wall construction, the combination of a course of rectangular units disposed layer upon layer to form one surface of a wall, a second course of similar rectangular units disposed layer upon layer in opposed parallel relation with said first course of rectangular units and forming the other surface of the wall, the rectangular units of each course being disposed in staggered relation with respect to each other in both a vertical and a horizontal plane, and spacing projections upon said rectangular units having a laterally extending foot at the ends thereof, the location of the spacing projections upon said rectangular units being such that two vertically extending aggregate containing cavities will be formed within the length of each of said rectangular units and the disposition of the foot portion upon the end of each of said spacing projections being such that they will extend alternately into an adjacent cavity and interlock with the aggregate in said cavity and hold the rectangular units of each course against vertical and lateral displacement.

JOHN JOSEPH OLSEN.
